UNITED STATES PATENT OFFICE

JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE

TYPEWRITING MACHINE

Application filed November 25, 1927. Serial No. 235,535.

This invention relates generally to means for facilitating the feeding of any one of a set of several fan-fold webs to a typewriting machine.

5 In many banks, communications in great variety are manifolded each day upon a web-typing machine, each kind being typed on a succession of like forms of a fan-fold web, which forms have headings different from the 10 forms of other webs. The operator, therefore, is required to change the webs in the machine many times each day. In devices heretofore proposed for facilitating the feeding of a large number of different work-webs, 15 one at a time, to a continuous-billing typewriting machine, the operator was obliged to rise from his seat and walk around behind the machine and pull the leading end of a work-web and its associated carbon-holder-frame out of a bin and place them in operative position on the typewriter.

It is an object of the present invention to provide means which will enable an operator of a continuous-billing typewriting machine 25 to conveniently change a work-web, together with its interleaved carbons, from the machine to a conveniently reached depository for future use without getting up and going behind the machine, and thereafter remove 30 from the depository and position in the machine, another carbon-holder-frame associated with a carbon-interleaved work-web fed from a conveniently-disposed web-pack.

In carrying out my invention, a continuous-billing typewriting machine is mounted on rubber-tired wheels which run on a laterally-disposed track fastened on a table-top. In the rear of said track is provided a depository 35 for a plurality of carbon-holder-frames which hold carbons interleaved between the leading ends of work-webs which are printed with different forms. The carbon-holder-frames are arranged in two rows, each being associated with a tier of containers under the 40 table for storing work-packs from which the

work-webs may be fed. Each of the carbon-holder-frames is arranged to be detachably mounted on a carbon-carrier-truck which has a forwardly-extending frame effective for moving the truck rearwardly to strip the carbon in the usual way.

To permit the forward rows of carbon-holder-frames to be positioned in the depository closely adjacent the rear rail without danger of collision with the laterally-movable typewriting machine, it is a feature of the present invention to omit the usual forwardly-extending operating handles from the carbon-holders, and mount an operating handle on the carbon-carrier-truck.

Other features and advantages will hereinafter appear.

In the accompanying drawings,

Figure 1 is a sectional view, front to rear, through a table arranged with a lateral track for a continuous-billing typewriting machine mounted on wheels and for co-operation with any one of a plurality of carbon-carrier-frames in the rear of the typewriting machine, said frames being associated with a plurality of work-webs fed from tiers of containers below said table.

Figure 2 is a fragmentary disassembled perspective view of a carbon-carrier, including a truck and a frame, employed in practicing the present invention.

Figure 3 is a fragmentary view of a rack or depository mounted on a table at the rear thereof for receiving a row of carbon-carrier-frames associated with idle work-webs disposed in containers below the table.

Figure 4 is a perspective view, partly broken away, of the typewriting machine, table, carbon-carrier-frames, etc., shown in Figure 1.

A continuous-billing typewriting machine 10, such as is disclosed in the patent to Fortin, No. 1,237,319, dated August 21, 1917, except as hereinafter set forth, may be mounted on four wheels 11, which may run on a top 12

of a table 12^a. The wheels may have rubber tires 13, and are fastened to a main frame 14 of the machine 10 by means of bracket-plates 15 and nuts 15^a. When the machine 10 is 5 rolled laterally to a desired operative position, for advantages to appear hereinafter, each front wheel 11 may be clamped against revolution to hold the machine fixed in that position. Means for clamping the front 10 wheels 11 may include a nut 16 and a handle 17. The wheels 11 and the above-noted devices co-operating therewith may be substantially the same as the construction disclosed in the co-pending application of A. E. Imbus, 15 Serial No. 14,379, filed March 10, 1925.

To provide for the machine 10 to be always moved laterally over the same path, a track including two channel-bar-rails 18, having 20 upturned flanges 18^a, is arranged for the wheels to run on, the rails extending all the way across the top 12 of the table and being 25 securely fastened thereto by screws 19. The widths of the channel-portions of the rails 18 are substantially the same as the widths of the tires 13. This construction of the rails co-operates with the clamping means for the rubber-tired wheels to hold the machine 10 fixed against creeping movement in any direction and also provides a cushioned mounting 30 for the machine.

For manifolding a multiple-ply work-web in a continuous-billing typewriting machine, carbon-sheets are interleaved between the plies of the web and are fastened to carbon-holding blades 29 mounted on usual stepped blocks 21 fastened on a carbon-holder-frame, generally designated as 22, and which is supported on a truck 23 of usual construction, except as hereinafter disclosed.

40 It has been found advantageous by many banks to type several kinds of daily communications in multiple on a set of fan-fold form-printed webs in a continuous-billing typewriting machine. It is usual for each 45 different kind of communication to be typed on a separate web, which bears different forms from those of the other webs, which necessitates that each of several webs be separately inserted in the machine preparatory to being 50 fed therethrough, and also to be removed from the machine when a different web is to be inserted. In some cases, it is necessary to insert and remove the same web two or more times during one day. To facilitate 55 inserting and removing each work-web of such a set in a continuous-billing typewriting machine, it has been proposed in the above-noted application of Imbus to keep the web-packs in tiers of box-containers under 60 a table at the rear thereof and to mount the typewriting machine on wheels for convenient lateral movement over said table to bring it in register with any desired one of said containers.

65 In the present invention, a forwardly-ex-

tending operating arm or handle 25 is mounted by screws 26 on a left-hand shelf-like extension 27 of a bed-plate 28, which forms an element of the truck 23. A short leftwardly-extending hand-piece 29 is mounted on the carbon-carrier-frame 22 by screws 30 for a purpose to presently appear.

The frame 22 may be detachably fastened to the truck 23 by means including two depending studs 31 fast on the frame, holes 32 in the bed-plate 28 disposed for receiving the studs, and latches 33 pivoted on the bed-plate, which fastening means may be substantially like those disclosed in the patent granted to Alfred G. F. Kurowski, No. 1,646, 70 966, dated October 25, 1927.

In practicing the present invention, fan-fold work-webs W are cross-folded to form work-packs P, which are kept in tiers of standard web-containers 34 of a usual box-like construction, the containers having their open ends up. Carbon-sheets are held in interleaved relation between the leading-end portions of the plies of each web W by the blades 20 of an associated carbon-holder-frame 22. To permit the work-web W to feed freely from a container in the lower tier, the containers in the upper tier are positioned forwardly a short distance relative to the lower containers, as shown in Figure 1.

When a carbon-holder-frame 22 is unlatched from the truck 23, the operative will grasp the short hand-piece 29 and lift the frame together with the forward end portion of the associated web W, and set the frame in one of two rows of carbon-holder-frames, constituting a depository 35, at the rear of the machine adjacent the rear edge of the table 12^a. One of the rows may be supported on a rack or shelf 36, which includes two angle plates 37 whose vertical members 37^a are spaced apart a proper distance to permit carbon-holder-frames 22 to be disposed between the vertical members for resting on a felt pad or cushion 38 lying on a flat metal plate 39, which is supported by horizontally-inreaching members 40 of the angle plate 37. The cushion 38 is effective for reducing the noise and shock resulting from placing the frames in the rack. The other row of carbon-carrier-frames may rest on the top 12 of the table 12^a adjacent the rear edge thereof. Each angle plate 37 has its ends fastened to rearward extensions 41 of angle plates 42 fastened to the sides of the top of the table 12^a by screws 43. The vertical members 44 of the angle plates 42 project above the top of the table 12^a and safeguard the laterally-movable machine 10 against being inadvertently rolled off the table.

A frame 22, when removed from the machine 10, is laterally positioned in the rear of the machine on the rear edge of the table or in the rack 36 so as to be disposed in the

same vertical plane as the container 34, which holds the work-pack P associated with the frame. The frames 22, holding carbons interleaved between the work-webs which are most frequently used during the day, will 5 preferably be placed along the rear edge of the table 12^a to have them as near the operative as possible.

It will be noted that employment in the 10 present invention of the short laterally-extending hand-pieces 29, in place of the usual long forwardly-extending handles 25, for lifting the carbon-holder-frames 22 from the truck 23, permits the frames to be positioned in the forward row of the depository 15 much nearer the laterally-movable machine 10 than would be possible if the usual frames having forwardly-extending arms were used. This arrangement also permits the rear row 20 of frames 22 on the rack 36 to be positioned in reach of the operator at the front of the machine, since only a narrow passageway 45 is required between the rack and the table-top 12 for feeding therethrough work-webs 25 from the upper tier of the containers 34. The feeding of a web W forwardly may be effected by rotating a usual platen by means of usual instrumentalities, not shown, or a finger-wheel 46 which will draw the web forwardly between side-edge guides 47 and 48 on a rod 49 on the rear end of a usual rear carriage-extension 50.

Variations may be resorted to within the 25 scope of the invention, and portions of the improvements may be used without others.

Having thus described my invention, I claim:

1. In combination, a web-manifolding, carbon-stripping typewriting machine having a carbon-carrier-truck on which is fastened a forwardly-extending operating handle, a table for said typewriting machine, a lateral track on the top of said table, rubber-tired wheels supporting said machine and running on said track, means for clamping said wheels to hold said machine stationary in any desired operative position, a plurality of carbon-holder-frames having leftwardly-extending hand-pieces, a depository in the rear of said machine for said carbon-holder-frames, each of said frames holding carbons interleaved between the plies of a temporarily idle fan-fold work-web arranged to be fed from a work-pack under the top of said table adjacent the rear side thereof, and containers for the work-packs arranged in two tiers, said frames being arranged in said depository in two lateral rows, the rear row being associated with work-packs in the lower tier of said containers, said depository including a rack for storing said rear row of frames, said rack being spaced a short distance to the rear of said table to leave a passageway therebetween for feeding webs from the upper tier

of containers to said machine, each frame in said depository being positioned to be in reach of an operator at the front of said machine when the latter is rolled laterally to an operative position in front of the frame. 70

2. In combination, a web-manifolding, carbon-stripping typewriting machine having a carbon-carrier-truck on which is fastened a forwardly-extending operating arm, a table for said typewriting machine, a lateral track on said table, wheels supporting said machine and running on said track, a depository for a plurality of carbon-holder-frames in the rear of said machine, each of said frames being arranged to be detachably mounted on said truck, and effective for holding carbons interleaved between the plies of a fan-fold work-web fed from a work-pack at the rear of said machine below the top of said table, a container for each of said work-packs, the containers being arranged in two tiers, and a rack in said depository for supporting in the rear of said table the frames which are associated with the work-packs in the lower row of containers, so that said frames may be conveniently grasped by an operative and placed on said truck one at a time, said rack being spaced to the rear of said table to leave a passageway for those of said webs which are fed from the upper tier of said containers. 85

3. In an organization of parts of the kind described, in combination, a plurality of carbon-holder-frames, a depository for said carbon-holder-frames arranged in two lateral rows, a table for supporting said depository, and a plurality of open-top, box-like containers below said depository for fan-fold work-webs cross-folded into work-packs, each work-web being associated with one of said frames, whereby the latter is effective to hold carbon-sheets interleaved between the plies of the web, said containers being arranged in two tiers, the upper tier resting upon the top of the lower tier and being set forward relatively to the latter to provide openings for each of the containers in the lower tier through which the work-web stored therein may lead to one of said frames in the rear row of said depository. 100 105 110 115

4. A work-table for a continuous-billing typewriting machine of the kind described, including a lateral track on said table and a depository in the rear of said track for a plurality of carbon-holder-frames arranged to be detachably mounted on said machine, one at a time, and to be positioned in two rows parallel to said track when idle, said depository including a laterally-disposed rack for one of said rows supported by said table and spaced a distance to the rear of the latter to leave a passageway for work-webs being fed to said machine from a source of supply below the top of said table, the other 120 125 130

of said rows being disposed along the rear edge of said table.

5. In combination, a continuous-billing typewriting machine having a rear carriage-extension, a table, means for moving said machine laterally over the same path on said table, including, in combination, wheels supporting said machine and a lateral track on said table for said wheels, and a depository in the rear of said machine for a plurality of idle carbon-holder-frames, each arranged for holding carbons interleaved between the plies of an idle fan-fold work-web which may be fed from a source below said depository to said machine over the rear end of said carriage-extension, said depository storing said frames in two lateral rows having a passageway therebetween parallel to said track and adjacent the rear end of said carriage-extension, whereby a work-web associated with the forward row of said frames may be drawn through said passageway when its associated carbon-holder-frame is operatively positioned on said machine for feeding said web to said machine.

6. In combination, a continuous-billing typewriting machine having a rear carriage-extension, a table for said machine, means for moving said machine laterally along said table over a fixed path, and a depository supported by said table in the rear of said machine for storing a plurality of idle carbon-holder-frames, each frame holding carbons interleaved between the plies of a fan-fold work-web to be fed from a source below said table to said machine, said depository including a laterally-disposed rack supported by said table and positioned to the rear thereof below the end of said rear carriage-extension, whereby some of the work-webs to be fed to said machine over said rear carriage-extension may pass in front of and some behind said rack.

7. In an organization of parts of the kind described, a rack for a plurality of carbon-holder-frames including two laterally-disposed angle plates having inreaching horizontal flange-members, a flat metal plate resting loosely on said flange-members, and a cushion-element on said flat plate upon which cushion said frames may be set noiselessly.

8. A work-support for a continuous-billing typewriting machine of the kind described, including a table, and a depository in the rear of said machine for carbon-holder-frames arranged to be detachably mounted on said machine one at a time, said depository including a laterally-disposed rack supported by said table and spaced a distance to the rear of the latter so as to leave a passageway for work-webs being fed to said machine from work-packs below the top of said table.

9. The combination with a typewriting machine having a web-manifolding paper-carriage, of means for enabling said carriage

to co-operate selectively with any one of numerous work-webs, including transverse tracks along which said machine may be set at different stations, in line with different work-web locations, means for retaining the machine at said stations, means for supporting, out of use, a set of carbon-carriers in rear of said machine at each of said stations, each of said carbon-carriers in each set being connectible to said carriage of said machine for manifolding the associated work-web, and separate sets of holders at the separate stations for the separate sets of webs, said sets of holders being disposed in the rear of the typewriter with their webs extending separately to the carbon-holders at each station, said sets of web-holders being arranged side by side, one set at each of said stations.

10. A selective web-manifolding apparatus as set forth in claim 9, having the carbon-holders at each station placed upon supports one behind the other, with the forward support spaced from the rear one sufficiently, to permit the upward travel of the web that is connected to the forward carbon-holder.
